UNITED STATES PATENT OFFICE.

LEONARD F. FULLER, OF PALO ALTO, CALIFORNIA, ASSIGNOR TO FEDERAL TELEGRAPH COMPANY, OF SAN FRANCISCO, CALIFORNIA, A CORPORATION OF CALIFORNIA.

RADIOTELEGRAPHY.

1,352,059.

Specification of Letters Patent.

Patented Sept. 7, 1920.

Original application filed April 23, 1917, Serial No. 163,793. Patent No. 1,330,254, dated February 10, 1920. Divided and this application filed September 23, 1918. Serial No. 255,245.

To all whom it may concern:

Be it known that I, LEONARD F. FULLER, a citizen of the United States, and a resident of Palo Alto, county of Santa Clara and 5 State of California, have invented certain new and useful Improvements in Radiotelegraphy, of which the following is a specification.

This application is a division of application Serial No. 163,793 filed in the Patent Office on April 23, 1917, and patented Feb. 10, 1920, No. 1,330,254.

The invention relates to means of signaling and particularly to means for signaling 15 with arc radio transmitters.

An object of the invention is to provide a signaling apparatus for high powered stations.

Another object of the invention is to provide 20 means for signaling by manipulating the direct current circuit.

The invention possesses other advantageous features, some of which, with the foregoing, will be set forth at length in the following description, where I shall outline in full that form of the invention which I have selected for illustration in the drawings accompanying and forming part of the present specification. It is to be understood however, that the invention as expressed in the 30 claims, is not limited to the specific embodiment shown in the drawings.

Referring to said drawings—

Figure 1 is a diagrammatic representation 35 of one form of the system.

Fig. 2 is a diagrammatic representation of a modified form of the system.

Heretofore, as far as I am aware, it has been considered essential in arc radio transmitters, to keep a practically constant radio-frequency load on the arc converter, when signals are being sent out. This has been accomplished in two ways; first, by the compensation method in which the arc is constantly loaded upon the antenna and the inductance in the antenna circuit varied and second, by the absorbing circuit method, in which a local non-radiating oscillatory circuit provided with a key is shunted around the arc, the constants of the circuit being so adjusted that when the key is closed, the arc would prefer to oscillate upon the local cir-

cuit or the antenna circuit, to the complete neglect of the other circuit. Both of these methods have proven satisfactory for medium-powered stations, but they have shown certain disadvantages for high-powered stations, mainly because each requires the handling of radio-frequency currents at telegraphic speed.

My present invention provides a means of signaling which necessitates the handling at telegraphic speed of only the current which feeds the arc, which may be direct current or alternating current, and this current may be easily handled.

In Fig. 1, I have shown one form of apparatus for signaling, by manipulating the arc feeding current, which in this instance, is direct current. The transmission system includes an arc oscillation generator 2 capable of producing continuous oscillations, having a negative electrode 3 which is grounded and a positive electrode 4 which is connected to the antenna 5 through the variable inductance or loading coil 6. Direct current is supplied to the arc by the generator 7, in the leads of which, choke coils 8 are placed. The arc is subjected to a strong transverse magnetic field produced by the winding 9 arranged in the negative lead. Shunting the arc is a circuit containing a variable resistance 12, and means are provided for opening and closing the resistance circuit. When the resistance circuit is closed, the current is shunted through the resistance 12, which is so adjusted that the load on the generator 7 remains the same as when the resistance circuit is open, and the arc is burning and setting up radio-frequency oscillations in the antenna. Thus the current in the arc magnet winding 9 is held constant, a feature which is necessary on account of the large inductance of the winding. This large inductance sets up a large voltage across the arc and this voltage or inductive kick, is sufficient to reignite the arc when the shunt circuit is opened. When the electrodes are cold however, and there is no ionization of the arc gap due to red-hot carbon, the arc will not usually be re-ignited and some auxiliary means are usually employed to accomplish this re-ignition.

The resistance circuit is closed and broken

within the arc generator and the arc produced by the opening of the resistance circuit is employed for re-igniting the main arc. In the system shown in Fig. 1, one 5 end of the resistance circuit terminates in a movable electrode 14, arranged within the arc generator and adapted to be moved from contact with electrode 4 to contact with electrode 3 and vice versa. The other end of 10 the resistance circuit is connected to electrode 4, so that a movement of the electrode 14 from electrode 3 to electrode 4, makes the main arc and a movement of electrode 14 from electrode 4 to electrode 3, breaks the 15 main arc. When the electrode 14 is in contact with the electrode 3, the direct current flows through the resistance circuit and the arc is extinguished. As the electrode 14 moves from electrode 3 to electrode 4, an 20 arc is drawn which re-ignites the main arc and short circuits the resistance. The electrode 14 is moved from contact with one arc electrode to the other by the key 15.

In the apparatus shown in Fig. 2, the 25 movable electrode 14, instead of being movable from one arc electrode to the other, is movable into and out of contact with the electrode 4, by the key 15. The electrode 14 is preferably arranged to move at substantially 30 right angles to the main arc gap, and as the resistance circuit is opened an arc is produced between the electrodes 4 and 14 and this arc bows out and is blown by the magnetic field into contact with the negative electrode 3, thereby igniting the main 35 arc.

I claim—

1. An arc system for radio signaling comprising two electrodes between which an 40 arc is formed, a resistance circuit having substantially the same resistance as the arc, connected to one of said electrodes, and a third electrode connected to the other side

of the resistance circuit and movable into contact with the other of said arc electrodes. 45

2. In an arc radio generator, two normally stationary electrodes between which an arc is formed and a third electrode movable into contact with one of the stationary electrodes. 50

3. In an arc radio generator, two normally stationary electrodes, means for producing an arc between said electrodes and a third electrode movable alternately into contact with said stationary electrodes. 55

4. In an arc radio generator, two electrodes between which an arc is formed, a third electrode movable into contact with one of said arc electrodes and a power consuming circuit connected to the third electrode and to the electrode on the other side of the arc. 60

5. An arc system for radio signaling, comprising two electrodes between which an arc is formed and means for signaling, comprising a third electrode movable into contact with one of said arc electrodes. 65

6. An arc system for radio signaling comprising two electrodes between which an arc is formed, a resistance circuit connected at one end to one electrode and a movable electrode connected to the other end of the resistance circuit movable into contact with the second arc electrode. 70

7. An arc system for radio signaling, comprising two electrodes, a generator connected to said electrodes whereby an arc is formed, a resistance circuit, and means including a movable electrode adapted to contact with an arc electrode, to shunt the current from the arc to the resistance circuit. 75

In testimony whereof, I have hereunto set my hand at Palo Alto, California, this 10th day of Sept. 1918.

LEONARD F. FULLER.
